UNITED STATES PATENT OFFICE.

WILLIAM W. BRADLEY AND JAMES R. HOLROYD, OF WASHINGTON, DISTRICT OF COLUMBIA.

ELECTRIC FIRING MECHANISM FOR GUNS AND SHELLS.

SPECIFICATION forming part of Letters Patent No. 372,958, dated November 8, 1887.

Application filed September 21, 1886. Serial No. 214,171. (No model.)

To all whom it may concern:

Be it known that we, WILLIAM W. BRADLEY and JAMES R. HOLROYD, of Washington city, District of Columbia, have invented certain new and useful Improvements in Electric Torpedoes; and we do hereby declare that the following is a full, clear, and exact description of the invention, which will enable others skilled in the art to which it appertains to make and use the same, reference being had to the accompanying drawings, and to the letters of reference marked thereon, which form part of this specification.

Our invention has relation to bombs or torpedoes and means for projecting and exploding them, and has for its object to furnish a spherical torpedo loaded with gunpowder, gun-cotton, dynamite, nitro-glycerine, or other explosive compound, and a mortar, cannon, or pneumatic gun by which it is to be projected, with means whereby both the gun and the torpedo may be fired by electricity, either by the gunner or by automatic machinery.

Our invention will be first fully described, and afterward specifically pointed out in the claims.

In the accompanying drawings, Figure 1 is a view in side elevation of the gun, the torpedo on its way from the gun, the coil of wire by which the bomb is to be reached by the electric current, and the stand for containing said coil, together with a plan view of the automatic circuit-closer or firing-board battery. Fig. 2 is a view in side elevation of the automatic circuit-closer or firing-board, and Fig. 3 is an end elevation of the same.

Like letters of reference mark the same parts wherever they occur in the various parts of the drawings.

Referring to the drawings by letters, A is a mortar, cannon, or pneumatic gun suitably mounted. B is a spherical torpedo of a size to suit the caliber of the gun, to which is attached, by a span, C, and suitable snap-hooks, a double electric cable, D, wound upon a conical drum E, mounted on a pivot, e, and adjustable by means of a toggle and screw, E', to suit the elevation of the gun. From the bottom of the cone E the cable D is extended, separated into two parts, D' and D", to a firing-board or circuit-closer, F, being connected to the tube

terminals g g'. Upon the firing-board is mounted on the pedestals G G' the brass shaft H, which carries an ebonite cylinder, H', and a brass disk, K, provided across the edge with a score or slot, which engages a catch or pawl, L, pivoted on a pedestal, L', mounted on the firing-board and having the spring l, which keeps it normally in contact with the disk, and a pawl, l', which forms a circuit-closer by contact with a brass plate, M, to which is attached a binding-screw, N. The binding-post g is insulated from the base-plate, and is connected, as shown, with one terminal of the torpedo-circuit and with one pole of the battery. The supports for the circuit-closer Q and metallic contact-spring O are insulated from the base-plate. The circuit-closer Q is connected with the other wire of the torpedo-circuit, and a metallic pin under the circuit-closer at g' is in metallic contact with the base-plate and with one pole of the battery. The plate M is insulated from the base-plate. The operation will now be understood. When the key L is depressed, the current flows from the upper pole of the battery through the igniter in A, back to the plate M, through key L and its support to the base-plate, across the base-plate to g', thence to the other pole of the battery. The depression of the key releases the rotating circuit-closer, which, after a partial revolution, brings pin R under spring O and closes a circuit from the upper pole of the battery to binding-post g, out on D' to torpedo, back on D" to the end of Q, thence by Q to pin R, posts G G', and by base-plate to g' and the other pole of the battery.

O is the contact-spring, supported by a brass pedestal, P, to which is connected another circuit-closer, Q, acting upon a brass plate connected to binding-post g'. The brass shaft H is prolonged, and has on it a train of gearing or clock-work, as shown at H", by which a rotary motion is imparted to said shaft.

Through the ebonite cylinder H' is a brass pin, I, which connects with the brass shaft H.

S is the battery, one of the poles of which is connected to binding-post g and the other to binding-post g'.

On the gun-carriage is a shelf, T, of ebonite, having two binding-screws, t t', (insulated from each other and from the carriage,) to

which are connected the wires of an electric primer inserted in the vent of the gun. One of these binding-screws, t' , is connected to the binding-screw N , and the other, t , is connected to the battery. The battery, or, as it may be, dynamo-machine, is of sufficient power to fire through the resistance of the cable D .

When the torpedo is placed in the gun or mortar, (the battery-current being broken at the battery,) the primer-wires are connected to the binding-screws t t' in shelf T , and then the battery-connection is made. When ready to fire, the circuit-closer L is pressed at its outer end, thus releasing N from the slot or score in disk K and allowing the shaft H and its ebonite cylinder H' to rotate, at the same time bringing the point t' into contact with the brass plate M , thus closing the circuit through the primer and firing the gun. When the ebonite cylinder has rotated a sufficient distance, the brass spring O comes in contact with the pin R , thus closing the torpedo-circuit. The rotation of the ebonite cylinder is governed by the pressure L on disk K , according as it is desired to accelerate or retard said rotation, such adjustment being made to suit the time of flight for the torpedo. Should it be necessary to fire the torpedo before the revolution is completed, the circuit-closer Q may be brought in contact with the brass plate secured to binding-screw g' , thus closing the circuit by hand, instead of automatically, and bringing the torpedo perfectly under the control of the operator. The firing-circuit in this case is from the upper pole of battery to g , through torpedo-circuit by D' D'' to g' , (and lever Q being depressed,) through contact on end of Q over g' to lower pole of battery. Should a pneumatic gun be used, the circuit through the primer is not used. The cable may be used in the form of a coil having the torpedo connected to the inner ends and drawing it thence, or by "flaking" the cable on the ground or deck of a ship.

Having thus fully described our invention, what we claim, and desire to secure by Letters Patent of the United States, is—

1. A gun or mortar mounted on a carriage and adjustable as to elevation and inclination, in combination with a separate carriage, a conical mandrel or reel mounted thereon capable of adjustment to correspond to the inclination of the gun, and cable to coil thereon, carrying at its outer end a torpedo to be fired from the gun, as set forth.

2. In combination, a gun or mortar, an electric primer for firing the same, a cable con-

nected to a torpedo to be fired from the gun, conductors connecting the gun and torpedo with a battery, and a battery and a firing-board provided with circuit-closers for consecutively closing the circuit through the primer for firing the gun and the torpedo during its flight, as set forth.

3. In combination, a gun, a battery, conductors connecting an electric primer on the gun with the battery, a cable connecting the battery with a torpedo, and a firing-board provided with means for closing the circuit through the primer and afterward automatically closing the circuit through the torpedo, as set forth.

4. In combination, a gun adjustable as to inclination, an electric cable connecting with a torpedo, a cone-carriage to receive said cable, adjustable to correspond with the adjustment of the gun, a battery, and a firing-board connected to the gun and projectile, whereby the projectile may be discharged and then exploded at a predetermined time, as set forth.

5. The combination of a gun-firing circuit, a torpedo-firing circuit, a battery for both circuits, a circuit-closer for the gun-circuit, and a rotatable circuit-closer for the torpedo-circuit normally locked against rotation by the gun-circuit closer, whereby the torpedo-circuit is closed a determinate period after the gun-circuit, substantially as and for the purpose specified.

6. The combination of an electric circuit through a gun, an electric circuit through an explosive projectile from the gun, a battery, a circuit-closer for the gun-circuit, and a time-circuit closer for the projectile-circuit, the former normally locking the latter against movement, but releasing the same when itself operated.

7. The combination of a torpedo-firing circuit, a battery in said circuit, and a circuit-closer in said circuit, consisting of a rotatable shaft, a circuit-closing pin carried by said shaft at one terminal of the circuit, a contact-spring in the path of said pin at the other terminal of the circuit, means for normally locking the shaft against rotation, and a releasing device to unlock the shaft, for the purpose set forth.

In testimony that we claim the foregoing as our own we affix our signatures in presence of two witnesses.
